UNITED STATES PATENT OFFICE.

JOHN B. WILSON, OF NEW YORK, N. Y.

VENEER.

SPECIFICATION forming part of Letters Patent No. 389,624, dated September 18, 1888.

Application filed October 8, 1887. Serial No. 251,797. (No model.)

To all whom it may concern:

Be it known that I, JOHN B. WILSON, of the city, county, and State of New York, have invented a certain new and useful Improvement in Veneers, of which the following is a full, exact, and clear description, reference being had to the accompanying drawings, in which—

Figure 1 is a sectional or edge view of one of my improved veneers. Fig. 2 is a perspective view of same. Fig. 3 is an edge or sectional view of another one of my said veneers having irregular corrugations. Fig. 4 is an end view of a knife and accompanying machinery adapted to produce my improved veneers. Fig. 5 is a front view of a part of Fig. 4, showing side view of the end presented in Fig. 4 and the remainder of the apparatus broken away, as being unessential to description.

20 My invention relates to a new and useful improvement in the manufacture of veneers.

Letters Patent for an improved veneer have been heretofore granted to me, No. 73,421. My present invention constitutes an improvement upon that described in said patent. By my said former invention I produced a veneer presenting a much more rich or complicated "figure" of grain than could be produced by the precedent method of cutting the veneer 30 from the log by means of a straight or flat cut. For the latter I substituted a waved, crimped, or corrugated cut; but a veneer produced by such waved, crimped, or corrugated cut, as described in my said former patent, and as 40 heretofore practiced by myself, is open to the objection that it often presents in parallel and unnatural looking stripes over its surface those portions of the figure of the wood which are the most enriched by such cut. Such cuts, 50 whose waves or corrugations are straight and parallel, frequently produce a veneer whose grain will at the tops and in the bottoms of the corrugations, as at A and B in the drawings, approximate closely to the figure of grain produced by an ordinary straight and level cut, while the grain produced by that portion of the cut extending between such top and bottom will, inasmuch as it separates the veneer 60 from the log at a greater or less angle, as at C in the drawings, more or less vary from the

appearance of the grain produced by such straight cut.

The enrichment of the appearance of the grain produced by my former invention has been great; but the said uniformity of variations has proved objectionable. The object of my present invention is to remedy this defect and to produce a veneer the grain of which shall be vastly richer in appearance than that of a veneer produced by either a straight or a 55 merely corrugated cut, and in which the variation and enrichment of the grain shall be so wavy and irregular as to more closely simulate nature. I attain this object by means of my invention, which consists in the production, 60 as a new article of manufacture, of a veneer having sinuous waves, crimps, or corrugations A and B, as shown in Fig. 2, which is a perspective view of a portion of one of my improved veneers as same is cut from the log 65 and prior to its being pressed out in the usual and well-known manner for application to another shaped surface.

In the production of my said improved veneers I propose to make use of machinery 70 and processes which will become the subject of a subsequent application for Letters Patent, inasmuch as I do not here wish to be confined to any particular instrument, machine, or process of cutting my said improved veneers, as 75 any apparatus which may be found expedient may be used to produce them, and a variety of processes might be employed with varying success. In order, however, that one method at least of producing my said improved veneers may be here described, I have illustrated same by one arrangement of knife and accompanying mechanical parts, which is competent 80 to produce the result desired.

It will be seen that by imparting sinuosity 85 to the corrugations in the direction of the latter's length the irregularity and variety of the appearance of the grain throughout the finished veneer is increased and a veneer produced of entirely different and greatly improved appearance as compared with that secured by said former Letters Patent. I also further add to the appearance of the figure of the grain by varying the depth, relative to each other, of each wave, crimp, or corrugation, as 90 95 100

illustrated by the sectional view, Fig. 3. By means of combining the said sinuosities with such variations in depth of corrugations infinite variety in the appearance of the grain 5 may be secured.

My improved veneer may be cut, as aforesaid, lengthwise of, crosswise of, or at any intermediate angle with the grain of the log.

As in the case of my said former invention, 10 I propose generally in the use of my improved veneers to press them out flat to apply to plane surfaces; but they may be made, adapted, and applied to corrugated or otherwise shaped surfaces with perfect facility, as will be understood by those familiar with the manufacture 15 and use of veneers.

What I claim as new, and desire to secure by Letters Patent, is—

1. As an article of manufacture, a veneer whose surface as cut from the wood contains 20 sinuous corrugations, substantially as and for the purpose described.
2. As an article of manufacture, a veneer whose surface as cut from the wood contains 25 sinuous corrugations of various depths, substantially as and for the purpose described.
3. As an article of manufacture, a veneer the surface of which as cut from the wood contains corrugations of various depths, substantially as and for the purpose described.

JOHN B. WILSON.
